UNITED STATES PATENT OFFICE.

BARTHOLOMEW P. BURNS, OF CHICAGO, ILLINOIS, ASSIGNOR OF ONE-FOURTH TO ANDREW DOBSCHER, OF CHICAGO, ILLINOIS.

CHAISE LONGUE.

Application filed November 28, 1922, Serial No. 603,797. Renewed September 30, 1924.

To all whom it may concern:

Be it known that I, BARTHOLOMEW P. BURNS, a citizen of the United States, residing at Chicago, in the county of Cook and State of Illinois, have invented certain new and useful Improvements in Chaise Longues; and I do hereby declare the following to be a full, clear, and exact description of the invention, such as will enable others skilled in the art to which it appertains to make and use the same.

The invention relates to a couch of the type of a chaise longue in which the back is adjustable, whereby the occupant may recline to a greater or less degree as may be required for comfort.

The invention aims to provide adjustable arms which are connected with the back for movement therewith, the arms being so mounted as to remain parallel with a normal position at each adjustment, whereby to maintain the relationship between the arms, back and seat.

The invention furthermore provides means for automatically elevating the back, said means being adjustable whereby to regulate the force exerted for lifting or counterbalancing the back.

The invention also contemplates means for securing the back in the required adjusted position, said means being readily releasable when it is required to effect adjustment of the back.

The invention furthermore provides an adjustable back which is concave on its upper side to materially add to the comfort of the occupant, the space between said adjustable back and the seat being covered by a suitable fringe or drapery which is attached to the back and movable therewith.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application.

Figure 1 is a side view of a chaise longue embodying the invention,

Figure 2 is a top plan view thereof,

Figure 3 is a detail plan view showing more clearly the operating means associated with the adjustable back,

Figure 4 is a side view of an end portion 60 of the longue partly in section and on a larger scale,

Figure 5 is a sectional detail on the line 5—5 of Figure 2,

Figure 6 is a detail view of one of the 65 arms and portions of the seat and back frames,

Figure 7 is an elevation of the parts shown in Figure 6,

Figure 8 is a detail view in perspective 70 of a portion of the back frame,

Figure 9 is a section detail on the line 9—9 of Figure 3, looking in the direction of the arrows,

Figure 10 is a detail view of the self-adjusting support for the outer end of an arm.

Corresponding and like parts are referred to in the following description and designated in the several views of the drawings by like reference characters.

The chaise longue as illustrated partakes of the nature of a sofa and comprises generally a seat A, a back B and arms C. The device is mounted upon legs D, which may be of any design and construction. The 85 main or seat frame comprises longitudinal rails 1 and end rails 2. The major portion of the seat is upholstered, whereas the rear portion occupied by the back B is without upholstery. Strips or webs 3 are attached to the longitudinal rails 1 and support springs 4 upon which rests the upholstering 5. These parts may be of any construction and arrangement common in the art of upholstering and according to the finish and cost of the article.

The rear portion of the rails 1 is widened as indicated at 5 and the upper edge is slightly curved. A corbel 6 is provided in advance of the widened portion 5 and the same is strengthened by means of a block 7 glued or otherwise attached to the inner side thereof. The back B is hinged to the upwardly projecting part, as indicated at 8, and is strengthened by means of a block 9 secured to the inner side of each member comprising the frame. A portion of the reinforced part of the frame is cut away as indicated at 10, and the arm C is hinged thereto as indicated at 11. The upper surface of the back B is made con-

cave, whereby to add materially to the comfort of the occupant. The back B comprises a suitable frame which is upholstered in a manner similar to the seat A, as shown most clearly in Figure 4, strips or webs 3 being attached to the frame and supporting springs 4 upon which is placed the upholstering 5. Fringe or other drapery 12 is attached to the lower portion of the frame comprising the back and is of sufficient length to cover the space formed between the back and seat when the back is adjusted or raised to the maximum degree of elevation. This fringe or drapery is of such make as to pend vertically and present a neat appearance and at all adjustments of the back cover the space formed between it and the seat so as not to expose any of the opening and thereby hide the operating mechanism associated with the back.

The arms C are suitably upholstered and are hingedly connected at their rear ends to the frame of the back B in any preferred way, as indicated at 11, and are adjustably supported at their front ends from the frame of the seat. The adjustable support comprises members 13 and 14 which are telescopically related, the member 13 being secured at its lower end to the corbel 6 of the rail 1 and inclining upwardly and forwardly to receive the member 14 which is attached to the arm C and depends therefrom at a rearward and downward inclination to correspond with the upward and forward inclination of the member 13. A curved slot 15 is formed in the member 14 and receives a pin 16 carried by the upper end of the member 13. The parts are relatively disposed to insure movement of the arms C with the back B, the member 14 sliding freely in the member 13 and at all stages of adjustment forming a support for the outer ends of the arms. When the back B is elevated, the arms C correspondingly rise, and when the back is lowered, the arms are similarly lowered. The connections are so arranged that the arms C always remain parallel to a given position when adjusted. The adjustment of the arms C is automatic and is concurrent with the adjustment of the back.

A transverse shaft 17 is secured at its ends to fittings 18 attached to the inner side of the rails 1. A drum 19 is loose upon the shaft 17 but prevented from moving longitudinally thereon. A toothed wheel 20 is provided at each side of the drum 19 and is loosely mounted upon the shaft 17 but, like the drum 19, prevented from moving longitudinally thereon. Each of the toothed wheels 20 is provided upon its outer side with a polygonal portion 21 to receive a wrench or other appliance to admit of rotating the toothed wheel when it is required to adjust the tension of a coil spring 22

mounted upon the shaft 17 and having connection at opposite ends with the drum 19 and toothed wheel 20, respectively. A spring actuated latch 23 is in cooperative relation with each of the toothed wheels 20 to hold the same in the required adjusted position and thereby maintain the tension of the spring 22. The spring actuated latches 23 are mounted in fittings 24 carried by a crosspiece 25. The drum 19 is provided with a toothed portion 26 with which a latch 27 cooperates to hold the drum in a given position. The latch 27 is mounted in a fitting 28 similar to the fittings 24, the fitting 28 being carried by the crosspiece 25. A shaft 29, mounted in the longitudinal rails 1 of the seat frame, has its ends projecting and provided with knobs 30, whereby the shaft may be turned when required. An arm 31, projecting from the shaft 29, is linked to the latch 27 so that rotation of the shaft 29 in one direction withdraws the latch 27 from engagement with the toothed portion 26 of the drum 19 which may then turn freely upon the shaft 17. A spring 32, mounted upon the shaft 29, is connected at one end to said shaft and at its opposite end to the adjacent rail 1. The spring 32 is normally under tension to rotate the shaft 29 in one direction so as to hold the latch 27 in engagement with the toothed portion 26 and thereby hold the drum 19 from rotating in either direction. The arrangement is such that the shaft 29 may be operated from either side of the longue as may be found most convenient. A curved bar 33, pivoted at its upper end to the back, depends therefrom and engages a bracket 34 secured to the crosspiece 2 at the rear end of the seat frame. The bar 33 is formed with a slot 35 which receives a pin 36 supported in the spaced elements of the bracket between which the bar 33 passes. A cable 37, or like part, is attached at one end to the lower end of the bar 33 and at its opposite end to the drum 19 and is partly wound upon the latter. The coil springs 22 are normally under tension which is regulated by turning the toothed wheels 20 and it is preferred to have the tension such as to effect an elevation of the back B when the drum 19 is released, this being accomplished by the winding of the cable 37 upon the drum by the action of the springs 22. When it is required to adjust the tension of the springs 22, the drum 19 is held stationary by engagement of the latch 27 with the toothed portion 26 thereof and the latches 23 are moved to clear the toothed wheels 20, which latter are rotated through the instrumentality of a wrench or other appliance fitted to the part 21. After the springs 22 have been properly tensioned, the latches 23 are permitted to engage the toothed wheels 20, thereby maintaining the tension imparted to the springs. Upon

operating the shaft 29 to disengage the latch 27 from the toothed portion 26, the drum 19 is rotated by the action of the springs 22, thereby winding the cable 37 thereon and 5 elevating the bar 33 and the back B. When the back reaches the required elevation, the shaft 29 is released, thereby throwing the latch 27 into engagement with the toothed wheel 26 and preventing further rotation of the drum 19 and holding the back B and the 10 arms C in the required adjusted position.

What is claimed is:

1. In a device of the character specified, a seat, a back pivoted to the seat, arms 15 having pivotal connection with the back and movable therewith, and telescoping supports between the outer ends of the arms and the seat and rigidly connected thereto, respectively, and inclining upwardly and forwardly away from the back.
2. In a device of the character specified, a seat, a back pivoted to the seat, arms pivoted to the back, and members rigidly 25 attached respectively to the seat and arms and having a telescopic arrangement and disposed relatively at an upward and forward inclination.
3. In a device of the character specified, a seat, an adjustable back, a rotatable drum, 30 connecting means between said drum and back, means coacting with said drum to hold the same in any required position, a rotatable toothed wheel, a spring connection between the toothed wheel and drum, the tension of 35 said spring being adjustable by rotation of the toothed wheel, and means independently of the first mentioned means for holding the

toothed wheel in the required adjusted position.

4. In a device of the character specified, 40 a seat, an adjustable back, a shaft, a drum loose on the shaft, toothed wheels loose on the shaft, spring connecting means between the toothed wheels and drum, latches for holding the toothed wheels in required adjusted position, a latch in cooperative relation with the drum for holding the same in required adjusted position, a manually operable shaft for releasing the latch coacting with the drum, and connecting means between said latch and manually operable shaft.

5. In a device of the class described, an adjustable back, a shaft below the back, a drum loose on said shaft, a cable connected 55 to said drum, means connecting said cable to the back, a cross piece below the back on the side of the shaft opposite to said means, a latch on said cross piece coacting with the drum, a toothed wheel loose on the shaft, 60 a helical spring surrounding the shaft and connected at one end to the drum and at the other end to the toothed wheel, and a latch operable independently of the first mentioned latch mounted on said cross piece and 65 coacting with the toothed wheel to regulate the tension of said spring.

In testimony whereof I affix my signature in presence of two witnesses.
